UNITED STATES PATENT OFFICE.

JOHN LOYN MARSHALL AND ROBERT EVAN DAVIS, OF FORT PAYNE, ALABAMA.

CIRCULAR-KNITTING MACHINE.

1,386,580.

Specification of Letters Patent.

Patented Aug. 2, 1921.

Application filed December 16, 1920. Serial No. 431,160.

To all whom it may concern:

Be it known that we, JOHN L. MARSHALL and ROBERT E. DAVIS, citizens of the United States, and residents of Fort Payne, in the county of Dekalb and State of Alabama, have invented certain new and useful Improvements in Circular-Knitting Machines; and we do hereby declare the following to be a full, clear, and exact description of the invention, such as will enable others skilled in the art to which it appertains to make and use the same.

This invention relates to stop mechanism for circular knitting machines,—one object of the invention being to provide simple and efficient means for causing the prompt stopping of a knitting machine when a hole occurs in the knitted fabric.

A further object is to provide an attachment for circular knitting machines, for effecting the stopping of the machine when a hole occurs in the knitted tube, and to so construct and arrange such attachment that its major portion shall be rotatable with the shaft of the knitting machine and occupy a position within the knitted tube, and so that a part of said attachment shall be movable in a downward direction and impart movement, through the medium of a lever located in proximity to the knitted tube, to means for stopping the machine when the said downwardly movable part of the attachment encounters a hole in the knitted tube.

With these and other objects in view, the invention consists in certain novel features of construction and combinations of parts as hereinafter set forth and pointed out in the claims.

In the accompanying drawings; Figure 1 is a view of a portion of a circular knitting machine showing the application of our improvements; Fig. 2 is an enlarged sectional view; Fig. 3 is a transverse section on the line 3—3 of Fig. 2, and Fig. 4 is a transverse section on the line 4—4 of Fig. 2.

1 represents a portion of a circular knitting machine and 2 the driven shaft thereof. The shaft 2 is provided in its lower end portion with a socket 3 to receive the shank 4 of a spindle 5. The lower end portion of the socketed part of the shaft 2 is provided with an L-shaped notch 6 to receive a pin 7 on the shank 4 and thus the spindle 5 is connected with the shaft 2 by a bayonet joint, so that its connection with said shaft

shall be movable. The socketed portion of the shaft 2 may have beveled portions 8 to guide the pin 7 into the L-shaped notch 6.

A collar 9 is secured to the upper portion 60 of the spindle 5, and to the lower end of said spindle, a collar 10 is secured.

Mounted loosely on the spindle 5 under the collar 9 is a circular block or member 11 which is supported in normal position by 65 means of a spring 12 encircling the spindle and bearing at its respective ends against said block or member 11 and the collar 10. The spring 12 presses the block 12 toward the collar 9 and in order that rotation of 70 the block 11 with the spindle 5 and shaft 2 under normal conditions shall be assured, without depending solely upon frictional engagement of the block with the collar 9, the collar is provided with a tit 13 to engage 75 a similar tit 14 on the block or member 11. These tits may be rounded (or beveled) so that when resistance is offered to the rotation of the block or member 11, the latter will, by the cam action of the 80 tits relatively to each other, be forced away from the collar 9 and thus be prevented from rotating with the spindle 5.

The block or member 11 is provided with a socket 15 in which a pin or finder 16 is 85 movable. A spring 17 is located in the socket 15 behind the pin or finder and operates to press the latter outwardly or radially with respect to the block, and cause its end to press against the tubular fabric 90 18 coming from the knitting machine as shown in Fig. 1,—said pin being thus adapted to be pressed through a hole which might occur in the fabric as indicated in Fig. 2. In order to prevent escape of the 95 pin or finder 16, the latter is provided with a groove 19 which receives the end of a screw 20.

The usual rolls 21 are provided for pulling or feeding the knitted tube lengthwise. 100

A lever 22 is pivotally mounted between its ends on a suitable pin or support 23 and one end of said lever is bent upwardly as at 24 and formed with a rounded or cam edge 25,—said lever being so located that its 105 cam arm 24 will normally lie near the cone of the tubular fabric and thus be disposed in the path of movement of the block or member 11 when the latter is caused to descend. The other arm, 26, of the lever 23 110 may be disposed between disks 27 on a rod or wire 28 of a Brinton stop motion, or

said arm 26 of the lever may be caused to operate any suitable means (not shown) to stop the operation of the machine.

- It will be observed that the attachment 5 which controls the operation of the lever 23 to stop the machine, is located inside of the cone of fabric and that during the normal operation of the machine, the said attachment rotates with the shaft, with the 10 spring-pressed pin or finder 16 bearing against the inside of the cone of fabric. Should a hole occur in the fabric tube, the pin or finder will be projected through it as shown in Fig. 2 and, as the fabric tube 15 continues to move longitudinally it will cause the block or member 11 to be moved downwardly on the spindle 5 away from the collar and its rotation will be arrested. As the block or member 11 thus moves 20 downwardly it will coöperate with the cam arm 24 (through the fabric) and cause the lever 23 to be turned on its pivotal mounting and operate the stop motion and thus stop the operation of the machine.
- 25 The attendant may readily detach the attachment from the shaft 2 of the machine to facilitate removal of the defective portion of the fabric tube and readjustment of said tube, and he may then connect the attachment with the shaft 2 and permit the block or member 11 to assume operative relation to the collar 9 so that said block or member will again rotate, with the pin or finder pressing against the cone of fabric.
- 30 Various changes might be made in the details of construction of our invention without departing from the spirit thereof or limiting its scope, and hence we do not confine ourselves to the precise details herein 35 set forth.

Having fully described our invention what we claim as new and desire to secure by Letters-Patent, is:—

1. The combination with a rotatable member of a circular knitting machine, of a part connected with said rotatable member and normally rotatable therewith, a spring-pressed finder carried by said part to engage the fabric tube and to enter a hole 45 therein, whereby said part may be connected with a defective fabric tube and caused to move therewith in the direction of travel of the fabric tube to disconnect said part from operative relation with the rotatable 50 member of the machine, and a lever for operating stop mechanism, said lever having an arm in the path of movement of said part when the latter is moved by the fabric tube.
2. The combination with a rotatable member of a circular knitting machine, of a spindle rotatable therewith, a member movable on said spindle in the direction of travel of a fabric tube coming from the machine, means normally connecting said member with the spindle so as to rotate there- 60

with, a spring pressed finder carried by said member and adapted to enter a hole which may occur in the fabric tube, and a lever for stop mechanism having a part in the path of movement of the member on the 70 spindle when said member is moved longitudinally of the spindle.

3. The combination with a rotatable part of a circular knitting machine, and a lever for operating stop mechanism, of a spindle 75 rotatable with the said rotatable part of the machine, a collar near one end of said spindle, a member on said spindle and movable longitudinally thereof, a spring pressing said member toward said collar, co-operable means on said collar and member to cause the latter to rotate with the spindle, and a spring-pressed finder carried by said member to engage a fabric tube coming from the machine, said member being co-operable with said lever when moved longitudinally of the spindle. 80

4. The combination with a rotatable shaft of a circular knitting machine, and a lever for operating stop mechanism, of a spindle 90 projecting from said shaft, a collar near one end of said spindle and having a tit, a member mounted on said spindle for operating said lever and having a tit for coöperation with the tit on said collar, a spring normally pressing said member toward the collar, and a spring pressed finder carried by said member to engage a fabric tube. 95

5. An attachment for circular knitting machines, comprising a lever for operating 100 stop mechanism, a spindle attachable to a rotatable shaft of a circular knitting machine, collars near respective ends of said spindle, a member loose on said spindle and movable longitudinally of the latter to operate said lever, said member and the collar near the upper end of the spindle having coöperable parts to cause said member to rotate with the spindle, a spring between the other collar and said member and operating to press the latter toward the upper collar, and a spring pressed finder carried by said member to engage a tubular fabric. 105

6. The combination with a rotatable shaft 110 of a circular knitting machine, and a lever for operating stop mechanism, of a spindle removably connected with said shaft, a member loose on said spindle and movable longitudinally thereof to operate said lever, 115 means for causing said member normally to rotate with said spindle, and a spring-pressed finder carried by said member and adapted to engage a fabric tube coming from said machine. 120

7. The combination with a rotatable shaft 125 of a circular knitting machine, and a lever for operating stop mechanism, said lever having a cam arm disposed near the path of a tubular fabric coming from the machine, 130

of a member normally rotatable with said shaft and movable in the direction of travel of a fabric tube coming from the machine to coöperate with the cam arm of said lever, 5 means for separably connecting said member with said shaft, and a spring-pressed finger carried by said member to engage the fabric tube.

In testimony whereof, we have signed this specification in the presence of two sub- 10 scribing witnesses.
